TUBE

Leopold Serog, Bielsko, Poland

Application January 26, 1938, Serial No. 187,080
In Poland January 29, 1937

4 Claims. (Cl. 221—60)

This invention relates to a tube for paste and similar materials.

The neck of known tubes is provided with a covered opening in the form of a projection, arranged eccentrically and introduced into a corresponding opening of the cap, this cap being riveted to a plug so that it can be rotated but not removed. The pressing out of the contents requires the removing of the cover of the opening by rotating the cap, the edge of which cuts off the projection. It is therefore necessary to use for the cap sheet-iron or a material, the hardness of which is greater than the hardness of the tube-material.

The invention avoids this disadvantage by arranging an eccentric opening in the upper surface of the neck, and a projection on the cap, corresponding to the opening, the lower edge of the cap being bent inwardly and introduced into a groove of the neck. The cap having no cutting effect can be made from the same material as that forming the tube. In other words the cap is formed of a relatively soft material, so that the projection can be removed easily with a knife or the like.

The neck-groove in which is introduced the lower edge of the cap serves as a guide for rotating the cap, so that no further means is necessary to retain the cap on the neck portion and thus reduce the cost of the closure means of the tube.

The material of the cap being the same as the material of the tube permits the entire contents of the tube to be expelled, as the cap can be pressed together by fingers. In known tubes such an operation is impossible by reason of the hardness of the cap-material.

The material of the cap can be also different from the material of the tube.

In the annexed drawing is shown an example of the tube according the invention.

Figure 1 shows the tube partly in front elevation and partly in section. Figure 2 is a horizontal plan view after removing the cap. Figure 3 is a sectional view taken on the line III—III in Figure 2. Figure 4 is a sectional view taken on the line IV—IV of Figure 2. Figure 5 shows the cap in section before fixing the same on the neck. Figure 6 is a top plan view of the cap. Figure 7 is a plan view of the interior of the cap. Figure 8 shows a modification of the cap.

The neck *a* of the tube *b* is provided in the end surface *a'* with an opening *c*, arranged eccentrically with respect to the axis of the tube. The neck is provided with an annular groove *e*, in

which is introduced the lower edge *f* of the cap *g*. The outer surface of the cap is provided with a projection *h*, so that after removing the same an opening *i* in the cap *g* is uncovered, corresponding to the opening *c*. On the inner surface *y* of the cap and at the corner formed by the skirt *d* an integral lug *k* is arranged which in rotating the cap moves on the tapered edge *l* of the neck. This edge is obliquely cut except the part *m*, the length of which being such, that in rotating the cap in one direction the lug *k* strikes one end of the part *m* and the cap stops in a position, in which the opening *c* is closed, while rotating the cap in the other direction causes the striking of the lug upon the other end of the part *m* and the position of the opening *i* is above the opening *c*.

In the modification according Fig. 8 a cap formed of material differing from the tube-material is employed. For example the cap may be formed of artificial resin. In this case the end *z* of the cap is provided with an opening *n*, corresponding to the opening *c* formed in the end of the neck *a*. The opening *n* is closed by a plate *o* of tinfoil or the like, the plate being introduced into the cap during production thereof. Into the groove *r* on the inner side of the skirt *p* of the cap a corresponding rib of the neck may be introduced. In using the tube the plate *o* can be easily perforated.

I claim:

1. In a collapsible tube, a cylindrical-shaped neck portion extending from the tube, a cover fixed to the neck and having an opening therein eccentrically arranged with respect to the axis of the tube, the outer edge of the neck portion adjacent the cover being tapered and a portion of said edge projecting beyond the tapered surface, a rotatable cap positioned over the cover and having a destructible closed opening therein capable of alignment with the opening in the cover, a lug carried within the cap and adapted to move along the tapered edge of the neck portion when the cap is rotated, and said lug being so positioned that the two openings are aligned when the lug engages the edge which projects beyond the tapered surface of the neck portion.

2. In a collapsible tube, a cylindrical-shaped neck portion extending integrally from the tube, a cover formed integrally with the neck and having an opening therein eccentrically arranged with respect to the axis of the tube, the major portion of the edge of the neck portion adjacent the cover being obliquely cut away to provide a stop member of the uncut edge, a rotatable cap positioned over the cover and having a destruc-

5 tible closed opening therein capable of alignment with the opening of the cover, a lug formed integrally from the cap and adapted to move along the oblique portion of the neck when the cap is rotated, and said lug being so positioned that the two openings are aligned when the lug engages the stop member.

3. In a collapsible tube, a cylindrical-shaped neck portion extending from the tube, a cover 10 formed integrally with the neck and having a circular opening therein eccentrically arranged with respect to the axis of the tube, the outer edge of the neck portion adjacent the cover being tapered and provided with a stop member pro-

jecting from the tapered edge, a rotatable cap positioned over the cover and having a circular aperture therein capable of alignment with the opening, a lug formed from an integral part of the cap adapted to move along the tapered edge of the neck portion when the cap is rotated, and said lug being so positioned with respect to the aperture that the opening and the aperture are aligned when the lug engages the stop member. 5

4. A collapsible tube according to claim 1 10 wherein the cap is formed of artificial resin and the destructible opening is closed by tin-foil embedded in the resin.

LEOPOLD SEROG.
